UNITED STATES PATENT OFFICE

2,573,236

MOUNTING FOR SLIDING DOORS

Alfred Ernest Whititt, Heston, Middlesex, England, assignor to James Whitson & Company Limited, West Drayton, Middlesex, England

Application February 17, 1947, Serial No. 729,015
In Great Britain February 14, 1946

3 Claims. (Cl. 20—23)

1

This invention relates to mountings for sliding doors and has for an object to provide a construction which will enable the door to lie within the doorway opening when in the closed position, with at least one face of the door flush with the doorway frame. Such an arrangement is particularly desirable for the door of a motor vehicle in order to give a neat appearance on the outside of the body.

According to this invention, a mounting for a sliding door comprises a guide track extending across the width of and beyond at least one upright margin of the doorway opening, and to one side of the plane of the opening a number of bracket arms each pivoted at one end, about an upright axis to the door and at the other, about an upright axis to a member guided along said guide track, the two pivot axes for each bracket arm being laterally displaced from each other, so that said door is capable of swinging bodily in a direction transverse to the plane of the opening and can also move in a direction along the length of the track. It will be appreciated with this arrangement that the door in effect is mounted on a parallel linkwork.

A guide track, a guided member and associated bracket arms may be employed for the top and/or bottom of the door. The aforesaid bracket arms may be so connected between the door and guided members that they are inclined in relation to the plane of the door, in such manner that an application of a force to the door in a direction to close it, also tends to swing it transversely into the plane of the opening, while a force applied to the door to open it, tends to swing it out of the plane of the opening. In order to enhance this action, a check device may be adapted to engage said guided member, or part attached thereto when the door is reaching the closed position, whereby continued movement of the door across the opening swings it in a positive manner into the opening.

At least the upright edges of the door and the doorway frame may be chamfered so as to fit one another when the door is in a closed position, and so as to facilitate the movement of the door into and out of the plane of the opening.

The upper part of the door may be underslung from the guided members in the track while the lower part of the door is arranged to overlap the guide track.

Each guide track may be provided with a single guided member movable along it to which said bracket arms are pivoted.

The guide track may be of the kind comprising a channel member arranged with its web portion upright, and the side flanges of which are provided with a number of balls or rollers spaced apart along the length thereof, and a bar-like guided member arranged within the chan-

2

nel with its side edges in engagement with said balls or rollers.

A catch is preferably provided for retaining the door in at least the closed position.

5 The following is a description of one embodiment of the invention, reference being made to the accompanying drawings, in which:

Figure 1 is an inside elevation of the door of a motor vehicle, and the mounting associated therewith, showing the door in a closed, or nearly closed, position, and

Figure 44 is a detail view of a portion of the door and its mounting.

if the block 19 or the bar 13 is arrested during the sliding of the door over the door opening, there will be a positive force closing the door into the opening. For this purpose, a check device 29 is secured to the doorway frame or body so as to have a trough-shaped part 30 arranged in the path of movement of a part 31 of said pin 18.

In order to ensure that the obliquity of the bracket member 15 is sufficient by the time that the check device engages the part 31, to enable the door to be readily swung into the door opening, there may be provided on the car body, beneath the bottom of the door opening, a curved guide block 32 which comes into engagement with a curved nose piece 33 on the door, so as to swing the door inwardly to the doorway opening just prior to the limit of its sliding movement.

As will be seen from Figure 2, the upright edges of the door are chamfered at 34 and the doorway frame is similarly chamfered at 35, at such an angle as to permit the inward and outward swinging of the door during its lateral movement. The doorway frame may be provided with overlying ledges 36 for obscuring any cracks around the door. Rollers 37 on the inside of the body are arranged to run on metal tracks 38 on the door and to guide the door during its movement to the fully open position.

A catch may be provided for securing the door in the closed position and the door may be provided with a handle, whereby the aforesaid movement may be applied to it.

I claim:

1. A sliding door construction comprising a door, a doorway frame, a guide track extending across the width of and beyond at least one upright margin of the doorway frame and disposed to one side of the plane of the frame, a guided member movable along said guide track, a number of bracket arms each pivoted at one end about an upright axis to the door and at the other end about an upright axis to the guided member and providing a parallel linkage between the door and the guided member, the two pivot axes for each bracket arm being laterally displaced from each other, an abutment member carried on the door intermediate of the ends of the door, guide means on the doorway frame in the path of movement of said abutment member so as to be engageable thereby when the door is approaching a position of register with the opening of the doorway frame, which abutment member and guide means when in engagement permit relative movement between them in the direction of said track, which movement causes the door to move towards the plane of the doorway frame, and stop means on the doorway frame arranged to arrest the guided member after the door has moved towards the plane of the doorway frame under the action of the guide means and abutment member and before closing of the door in the frame.

2. A sliding door construction comprising a door, a doorway frame, a guide track extending across the width of and beyond at least one upright margin of the doorway frame and disposed to one side of the plane of the frame, a guided member movable along said guide track, a number of bracket arms each pivoted at one end about an upright axis to the door and at the other end about an upright axis to the guided

member and providing a parallel linkage between the door and the guided member, the two pivot axes for each bracket arm being laterally displaced from each other and both lying in an upright plane inclined in relation to the plane of the door when the door is closed, an abutment member carried on the door intermediate of the ends of the door, guide means on the doorway frame in the path of movement of said abutment member so as to be engageable thereby when the door is approaching a position of register with the opening of the doorway frame, which abutment member and guide means when in engagement permit relative movement between them in the direction of said track, which movement causes the door to move towards the plane of the doorway frame, and stop means on the doorway frame arranged to arrest the guided member after the door has moved towards the plane of the doorway frame under the action of the guide means and abutment member and before closing of the door in the frame.

3. A sliding door construction comprising a door, a doorway frame, a guide track extending across the width of and beyond at least one upright margin of the doorway frame and disposed to one side of the plane of the frame, which guide track is formed by a channel member having its web portion upright and having a number of rotatable bearing units spaced apart along the length of its side flanges, a bar-shaped guided member movable along said guide track within said channel with its side edges engaged with said rotatable bearing units, a number of bracket arms each pivoted at one end about an upright axis to the door and at the other end about an upright axis to the guided member and providing a parallel linkage between the door and the guided member, the two pivot axes for each bracket arm being laterally displaced from each other, an abutment member carried on the door intermediate of the ends of the door, guide means on the doorway frame in the path of movement of said abutment member so as to be engageable thereby when the door is approaching a position of register with the opening of the doorway frame, which abutment member and guide means when in engagement permit relative movement between them in the direction of said track, which movement causes the door to move towards the plane of the doorway frame, and stop means on the doorway frame arranged to arrest the guided member after the door has moved towards the plane of the doorway frame under the action of the guide means and abutment member and before closing of the door in the frame.

ALFRED ERNEST WHITTIT.
